SNAP-HOOK.

1,296,217.

Specification of Letters Patent.

Patented Mar. 4, 1919.

Application filed July 6, 1917. Serial No. 178,907.

To all whom it may concern:

Be it known that we, JOHN R. REYBURN, of Fairfield, Fairfield county, Connecticut, and CLAUDE D. SAGENDORF, of Bridgeport, 5 Fairfield county, Connecticut, have made a certain new and useful Invention Relating to Snap-Hooks, of which the following is a specification, taken in connection with the accompanying drawing, which forms part of 10 the specification.

This invention relates especially to sheet metal snap hooks in which the hook member is formed of sheet metal bent up into channeled form in which the substantially parallel side plates are supported by the connecting and strengthening back web at such distance apart as to accommodate the flat spring strip used as the snap. These side plates may be given any desired hook form 15 and have their ends spaced apart and more or less closed by alining closing tips serving to hold the spring snap in place when in its holding position. The spring snap is also preferably provided with a transversely extending retaining spring end extending across the receiving hook recess in which the ring or other member to be held is inserted and this spring end preferably normally extends more or less into a spring slot in the 20 back web of the hook member so as to be still more securely held in this retaining position. When releasing the snap this spring end may project through the spring slot so as to open the hook and allow the withdrawal or insertion of the coöperating connecting member or device.

In the accompanying drawing showing in a somewhat diagrammatic way illustrative embodiments of the invention,

40 Figure 1 is an elevation of a blank from which the hook member may be formed.

Fig. 2 shows the completed snap hook in side elevation.

Fig. 3 is a corresponding front view, and 45 Fig. 4 is a back elevation thereof.

Fig. 5 is a side elevation of another form of snap hook of this general construction; and

Fig. 6 is a front elevation thereof.

50 These snap hooks may be cheaply and conveniently made by stamping them up from sheet steel or other suitable sheet metal and for ordinary snap hooks, such as are used for harness connections and similar purposes

ordinary low carbon steel is a suitable material. Fig. 1 shows the contour of a blank from which a snap hook of this type may be formed, the aperture 2 leaving web portions 4 and a connected apertured end plate 24 from which a swivel connection may be 55 formed, while the projections 6 are given such contour as is desired to form the particular shaped hook ends required for the particular purpose intended. The dotted vertical lines indicate the way in which the 60 side plates 1 of the blank may be bent up around the back web 9 in which may be formed a spring slot 8 and an anchor slot 5 when the locking tongue 10 is forced inward. As shown in Figs. 2 and 3 this blank is bent 65 up into channeled form so that the two side plates 1 are substantially parallel and are connected and strongly reinforced by the back web 9. The hooked ends 6 are preferably maintained in substantial alinement by 70 one or more suitable closing tips 7 which may be in the form of integral inturned tips bent up from these hook ends and soldered or otherwise connected, if desired, so as to 75 still more rigidly hold these hook ends in 80 alined parallel position.

In this way the hook member is in the form of a channel, the side plates being separated by such distance as to conveniently accommodate the spring snap which may be 85 in the form of a flat spring 13 of such width as to freely operate in this channeled hook member to which it may be connected in any desired way. One convenient form of mounting for the snap is to extend its end 90 into the curved spring loop 21 and recurved anchor end 11 which may be held in position in any suitable way as by passing through the anchor slot 5 formed by forcing up the locking tongue 10 which may be conveniently done when the blank is bent into the 95 channeled hook form described. The spring snap may be further supported as by forming inwardly protruding spring bearing projections 12 in the side plates 1 as by punching or forcing them inward to produce approaching more or less conical or cylindrical bearing projections holding the spring loop in substantial alinement while readily allowing its operating movement. It is quite desirable to form a transversely extending retaining end 23 on the spring snap substantially closing the receiving hook recess 23

and retaining therein the ring or other connecting member or device inserted in the hook so that it cannot twist or work down into engagement with the lower part of the 5 spring snap so as to force it out into released position. This retaining spring end may with advantage be guided or held against downward movement by any suitable projections or portions on the hook member and 10 this may be conveniently done by having the spring end project sufficiently back from the closing tips 7 against which the spring snap normally rests so that this spring end lies within the spring slot 8 and is thereby held 15 against displacement. The slot thus acts as a guide during the disengaging movement of the spring snap which may be readily forced inward by thumb pressure upon it so that its retaining end may protrude through the 20 spring slot and allow the coöperating ring 27 or other member to be withdrawn from or inserted in the receiving recess 26.

If desired, a swiveled connection may be provided on this spring snap by twisting the 25 apertured end plate 24 into the transverse position indicated in Figs. 2 and 3, the connector yoke 4 being preferably spread apart at this point so as to leave additional room for the coöperating swivel member. A sheet metal swivel is shown as formed with the 30 heads 14 inserted through the slot 3 which may then be forced together into substantially square shape by forcing the end plate 24 together vertically as it is shown in Fig. 1 35 so that the aperture 3 is thereby crowded together into substantially square shape with rounded ends to thus permanently retain the head 14 of the swivel member 15 in position while allowing free rotation thereof. This 40 swivel action is not, however, necessary in all cases and as shown in Figs. 5 and 6 the hook member may be formed with rivet connector holes through which a rivet 17 may extend in such position as to serve as a bearing 45 member for the spring snap 18 which may curve around this rivet and be formed with an anchor end, such as 19, coöperating or interlocking with a suitable projection which may be bent up from the web. If desired the locking tongue 20, which may be 50 formed integral with the back web, may be bent up to be engaged by this locking tongue and also preferably bent back against the spring end so as to still more securely hold 55 the spring snap in proper operative position in connection with the rivet and hook member. As indicated the rivet may pass through a suitable connector link 28, the rivet heads 29 being spun up or otherwise 60 formed outside of this link so as to hold it in proper cooperation with the hook member, although preferably allowing some swiveling movement between these parts.

This invention has been described in connection with a number of illustrative em-

bodiments, forms, proportions, sizes, arrangements of parts, materials, and methods of construction and use, to the details of which disclosure the invention is not of course to be limited, since what is claimed as 70 new and what is desired to be secured by Letters Patent is set forth in the appended claims:

1. The snap hook comprising a channeled sheet metal hook member having similar 75 side plates provided with hook ends connected and held in substantially parallel position by an integral back web, integral alining closing tips formed on said hook ends to connect and maintain their ends in substantially parallel position, a spring snap of such width as to fit loosely within the channel formed by said side plates and having a curved bearing portion and a recurved anchor end projecting through an anchor slot 80 in said back web, an anchor locking tongue formed on said web and engaging said anchor end, inwardly protruding integral spring bearing projections formed in said side plates to project into and coöperate 85 with the bearing portion of said spring snap, a transversely extending retaining spring end formed on said spring snap to normally extend across the receiving recess of said hook ends and project into a spring slot in 90 the back web.

2. The snap hook comprising a channeled sheet metal hook member having similar side plates provided with hook ends connected and held in substantially parallel position 100 by an integral back web, integral alining closing tips formed on said hook ends to connect and maintain their ends in substantially parallel position, a spring snap of such width as to fit loosely within the channel formed by said side plates and having a curved bearing portion and a recurved anchor end projecting through an anchor slot 105 in said back web, an anchor locking tongue formed on said web and engaging said anchor end, inwardly protruding integral spring bearing portions formed in said side plates to project into and coöperate with the bearing portion of said spring snap.

3. The snap hook comprising a channeled 115 sheet metal hook member having side plates provided with hook ends connected and held in substantially parallel position by an integral back web, integral alining closing means formed on said hook ends, a spring 120 snap of such width as to fit loosely within the channel formed by said side plates and having a curved bearing portion and a recurved anchor end, an anchor locking tongue engaging said anchor end, and inwardly protruding integral spring bearing projections 125 formed in said side plates to project into and coöperate with the bearing portion of said spring snap.

4. The snap hook comprising a channeled 130

- sheet metal hook member having side plates provided with hook ends connected and held in substantially parallel position by an integral back web, integral alining closing means formed on said hook ends, and a spring snap of such width as to fit loosely within the channel formed by said side plates and having an anchor end operatively connected to said hook member.
10. 5. The snap hook comprising a channeled sheet metal hook member having side plates provided with hook ends connected and held in substantially parallel position by an integral back web, integral closing means formed on said hook ends, a spring snap of such width as to fit loosely within the channel formed by said side plates and having a portion operatively connected to said hook member, a transversely extending retaining 20 spring end formed on said spring snap to normally extend across the receiving recess of said hook ends and project into a spring slot in the back web.
6. The channeled sheet metal snap hook member having similar side plates provided with hook ends connected and held in substantially parallel position by an integral back web, integral alining closing means formed on said hook ends to maintain their
- ends in substantially parallel position, an anchor locking tongue adapted to engage a spring, such inwardly protruding integral spring bearing projections formed in said plates to project into and coöperate with the bearing portion of the spring snap, said hook member being formed with an integral connecting yoke and apertured end plate adapted to coöperate with a swivel member.
7. The channeled sheet metal snap hook member having side plates provided with hook ends connected by an integral back web, inwardly protruding integral spring bearing projections formed in said side plates to project into and coöperate with the bearing portion of the spring snap.
8. The channeled sheet metal snap hook member having side plates provided with hook ends connected by an integral back web, said hook member being formed with an integral connecting yoke and apertured end plate adapted to coöperate with a swivel member.
